ABSTRACT

A cone-shaped magnetic core structure for receiving toroidal beam deflection coils for use with cathode ray tubes. The magnetic core structure has attached to the respective front and rear ends thereof relatively large and small diameter grooved insulating structures. The grooves in the insulating structure are mutually arranged so that in one pair of opposite quadrants looking along the central axis of the core grooves of the rear insulating structure are aligned with even-numbered grooves in the front insulating structure. In the other pair of opposite quadrants the grooves of the rear insulating structure are aligned with odd-numbered grooves of the front insulating structure.

FIG. 3.

COIL WINDING

The present invention relates to the winding of electric coils and is specifically concerned with the winding of toroidal beam deflection coils for use with cathode ray tubes.

In order to facilitate the winding of turns of wire on to a generally cone-shaped magnetic core so as to afford a pair of diametrically opposite horizontal deflection coils and a pair of diametrically opposite vertical deflection coils, it is known to fit relatively large and small grooved insulating ring structures to the front and rear ends of the core, respectively with the front ring having twice as many grooves as the rear ring for receiving the turns of wire. Accordingly, when all of the equispaced grooves of the front ring structure are occupied by turns of wire to form a single layer such turns of wire will be arranged in two layers at the rear end of the core, the turns of the first layer occupying the equispaced grooves of the rear ring structure and the turns of the second layer occupying the troughs between adjacent turns of the first layer. In this construction the grooves in the rear insulating structure are aligned with respect to alternate grooves in the front insulating structure and the four coils are balanced symmetrically about the central axis of the core.

However, the construction just above referred to does not permit of the four coils being wound on the core simultaneously thereby affording a significant saving in manufacturing costs, since insurmountable difficulties arise in connection with the requisite symmetry of the coils about the core axis as will hereinafter be apparent.

With a view to overcoming these difficulties there is provided a magnetic core structure as aforesaid having grooved front and rear insulating structures of relatively large and small diameters, in which the grooves in the insulating structure are mutually arranged so that in one pair of opposite quadrants looking along the central axis of the core grooves of the rear insulating structure are aligned with even-numbered grooves in the front insulating structure and in the other pair of opposite quadrants the grooves of the rear insulating structure are aligned with odd numbered grooves of the front insulating structure. This arrangement according to the present invention is preferably achieved by modifying the spacing between the grooves in the rear insulating structure close to the boundaries between quadrants.

By this arrangement of the grooves the two vertical and two horizontal coils can be wound simultaneously without significant loss of symmetry about the core axis.

5 For a better understanding of the present invention reference will now be made to the accompanying drawings in which:

FIG. 1 shows a cross-sectional view taken through the central axis of a conventional magnetic core structure 10 for beam deflection coils,

FIG. 2 is a diagram that illustrates the arrangement of coil turns in the grooves or slots of the moulded insulating structure of FIG. 1: and,

FIG. 3 is a diagram similar to FIG. 2 but which shows 15 how the spacing of grooves in the rear insulating structure is modified to facilitate the simultaneous winding of all the deflection coils.

Referring to FIG. 1 of the drawings, a generally cone-shaped magnetic (e.g. ferrite) core E has moulded insu-

20 lating rings F and G fitted to what may be regarded as the front and rear ends of the core E. Both of the rings F and G have grooves or slots H and I moulded therein for receiving the turns of beam deflection coils. These coils comprise two vertical deflection coils which are 25 wound on the core E at diametrically opposite positions and two horizontal deflection coils also arranged diametrically opposite to one another as will be better appreciated from FIG. 2. A single turn of one of the vertical deflection coils is indicated at J in FIG. 1.

30 Turning now to FIG. 2 which shows fragmentarily how the turns of wire forming the coils are located in the grooves or slots of the insulating rings F and G, the horizontal coils are designated coils A and B and the vertical coils designated coils C and D. These coils extend over the respective arcs indicated approximately 35 in the Figure. The insulating ring F has 288 grooves or slots equally spaced therearound, (only a few of the slots are shown in the figure) whereas the smaller insulating ring G has 144 grooves or slots equally spaced therearound and it is arranged that the grooves in the ring G are radially aligned with alternate grooves or slots in the larger ring F as shown in the Figure. First layer coil turns on the ring G may be wound in the odd-numbered grooves or slots of the ring F whereas second layer turns on the ring G may be wound in even-numbered grooves or slots of the ring F.

40 One possible winding distribution arrangement is indicated in the following table I.

TABLE I

Slot Nos. in ring 2													
Horizontal coil A:													
1st layer turns...	11,	13,	15,	17,	19,	21,	23,	27,	31,	33,	34,	35,	37,

1st layer turns...	59,	61,	63,	65,	67,	68,	69,	70,	71,	72,	73,	74,	75,
2d layer turns...	58,											76,	
1st layer turns...	77,	79,	81,	83,	85,	87,	88,	89,	90,	91,	93,	94,	95,
2d layer turns...	78,											96,	
1st layer turns...	97,	99,	101,	103,	105,	107,	109,	111,	112,	113,	115,		
2d layer turns...	98,		100,										
1st layer turns...	119,		123,	125,	127,	129,	131,	133,	135,				
Vertical coil C:													
1st layer turns...	80,	82,	84,	86,	89,	102,	104,	106,	108,	110,	114,		
2d layer turns...													
1st layer turns...	117,	118,	120,	121,	122,	124,	126,	128,	130,	132,	134,		
2d layer turns...	116,												
1st layer turns...	137,	138,	139,	141,	143,	145,	147,	148,	149,	150,	151,	152,	153,
2d layer turns...	136,		140,	142,	144,	146,	148,	150,	152,	154,	156,	158,	160,

Table I—Continued

Slot Nos. in ring 2													
1st layer turns...	149,	151,	153,										
2d layer turns...	148,	150,	152,	154,	156,	158,	160,	162,	164,				
1st layer turns...		169,		173,									
2d layer turns...	166,	168,	170,	172,	174,	176,	180,	182,	184,	186,	188,		
1st layer turns...													
2d layer turns...	198,		204,	206,	208,	210,							

NOTE.—Coils B and D can be distributed identically as A and C respectively but 180° removed from A and C.

In order to achieve symmetry of the coils the turns of that part of coil A in quadrant 2 must be placed in odd-numbered slots or grooves in the ring F to provide a mirror image of that part of horizontal coil A in quadrant 1. If the coils A, B, C and D are wound simultaneously these grooves or slots will already have been filled by turns of vertical coil C which must be wound first in grooves aligned with grooves on the internal bore.

Turning now to FIG. 3 this shows fragmentarily how the spacing between the grooves or slots of smaller insulating ring G¹ is modified from the known arrange-

10 71, but out of position equivalent to half the angle between slot 71 and 72 on the inner diameter. This small error in positioning one turn is considered to be acceptable but it is possible to further modify the small diameter ring moulding so that the groove for the turn wound in external slot 73 is moved through a small angle in order to compensate. A further modification of this would be to move through an even smaller angle the groove or slot for turns wound in the slots 73 and 75. One possible winding distribution for the arrangement described according to the invention is shown in Table II.

TABLE II

Slot Nos.

2d layer turns...	165,	167,			169,	171,								
1st layer turns...											207,	209,		
2d layer turns...	187,				193,			197,		203,				

NOTE.—Coils B and D can be distributed identically as A and C respectively but 180° removed from A and C.

ment of FIG. 2 in order to enable all of the four beam deflection coils designated A, B, C and D in FIG. 2 to be wound simultaneously without significant loss of symmetry of coils with respect to the central axis of the core. As can be seen in FIG. 3 the slots or grooves in the rear moulding G¹ are aligned with even-numbered slots on the front moulding F¹ in quadrant 1 and aligned with odd-numbered slots of the front moulding in quadrant 2. The grooves in quadrants 3 and 4 will be as shown for quadrants 1 and 2, respectively.

It can be seen that a second layer turn placed in slot 60 77 in the quadrant 2 will be at the same angle below the horizontal axis as a first layer turn placed in slot 70 in quadrant 1.

It will be seen however from FIG. 3 that the turn wound in slot 71 in the quadrant 1 which should match 65 the turn wound in slot 75 in the quadrant 2 will move out of position at the small diameter end. This occurs because the position of the turn will be controlled by turns wound in slots 70 and 73 in the first layer. Thus this turn will fall correctly at the outer diameter in slot

50 50 What we claim is:

1. A magnetic core structure of generally truncated-core shape for receiving toroidal beam deflection coils of cathode-ray tubes, said magnetic structure having attached to it grooved front and rear insulating structures of relatively large and small diameters for receiving the turns of said coils, in which the grooves in the insulating structure are mutually arranged so that in one pair of opposite quadrants looking along the control axis of the core grooves of the rear insulating structure are aligned with even-numbered grooves in the front insulating structure and in the other pair of opposite quadrants grooves of the rear insulating structure are aligned with odd-numbered grooves of the front insulating structure.

2. A magnetic core structure as claimed in claim 1, in which the alignment between grooves in the rear and front insulating structures is achieved by modifying the spacing between the grooves in the rear insulating structure close to the boundaries between quadrants.
